UNITED STATES PATENT AND TRADEMARK OFFICE
CERTIFICATE OF CORRECTION

PATENT NO. : D785,045 S
APPLICATION NO. : 29/551124
DATED : April 25, 2017
INVENTOR(S) : Coffman et al.

Page 1 of 1

It is certified that error appears in the above-identified patent and that said Letters Patent is hereby corrected as shown below:

On the Title Page

In the "DESCRIPTION" section, please insert the following omitted paragraphs after the figure description:

--The outermost broken lines in the Figure show a display screen or portion thereof, and form no part of the claimed design.

The bracket shown in the Figure indicates a group. The elements of the group are arranged relatively on the drawing sheet for the convenience of illustration, and the placement of each element relative to another, or to the drawing sheet, forms no part of the claimed design.--

Signed and Sealed this
Twenty-third Day of April, 2019

Andrei Iancu
Director of the United States Patent and Trademark Office
